[57] CLAIM

The ornamental design for a chair, or similar article as shown and described.

DESCRIPTION

FIG. 1 is a right side perspective view of the new chair design;

FIG. 2 is a rear elevational view thereof;

FIG. 3 is a top plan view thereof;

FIG. 4 is a front elevational view thereof; and,

FIG. 5 is a left side elevational view thereof.

The back of the chair is characterized in part by runs of rope woven in a straight pattern and transversely spaced at the bottom end by one wrap of rope around a support and at the top end by two wraps of rope around a support.

FIG. 1

FIG. 2

FIG. 3

FIG. 4
